UNITED STATES PATENT OFFICE.

FREDERICK KOHNLE, OF DAYTON, OHIO, ASSIGNOR, BY MESNE ASSIGNMENTS, TO THE MONARCH TAG COMPANY, A CORPORATION OF OHIO.

PRINTING AND SEVERING DEVICE FOR TICKETING-MACHINES.

1,197,037.

Specification of Letters Patent.

Patented Sept. 5, 1916.

Original application filed March 11, 1912, Serial No. 683,162. Divided and this application filed June 17, 1914. Serial No. 845,724.

To all whom it may concern:

Be it known that I, FREDERICK KOHNLE, a citizen of the United States, and residing at Dayton, in the county of Montgomery and State of Ohio, have invented a new and useful Printing and Severing Device for Ticketing-Machines, of which the following specification is a full disclosure.

This invention is divisional from an original application filed by me, March 11, 1912, Serial No. 683,162, for an improvement in stapling machine. The machine of which the invention herein is a component, as set forth in said application, operates upon gangs of prestapled tags, so as to feed the same at intervals or step advances toward printing devices for printing the desired tag data thereon; severing devices for separating the individual units from the gang or strip; and stapling devices for securing the tag individually upon the goods or material to be ticketed, or issue or deliver separate tags for subsequent use or manual application. The parent case, above referred to, elaborately and in detail discloses and describes the devices for supporting and feeding the gang or strip of tags, to feed the same longitudinally and properly direct and position each tag for the various performances of the machine, and, therefore, said application may be recognized as a part hereof to supply omissions herein as to details with which this application is not directly concerned. In this regard it may be noted that the feeding mechanism is somewhat coherent to the invention herein for operating upon a particularly formed gang tag strip, and it therefore is included in the combination with the printing and severing mechanism which forms the foundation for this invention.

The invention herein relates to rigidly combining type-holding and cutter devices operating as a unit with an actuator which also provides a support therefor to simplify the construction and obtain positive actuation, convenient accessibility for quick removal of the parts, which is very essential, especially as to the type-holder, by reason of the necessitated frequent change of printing data, all having an ultimate aim to increase the efficiency of the mechanism as well as preserve its life.

An object therefore of my invention is to

reduce the number of movable or translatable parts of a machine of this class and to combine the available parts into a compact and rigid unit.

Another object of my invention is to provide an actuator having a reciprocating motion substantially supported and guided for rigidly supporting a removable type-holder or chase in a plane above the feeding path or track of the tags, and also a rigidly supported removable cutter blade adjacent the type-holder, so that both holder and blade operate simultaneously upon the tag strip. Thus a tag strip is printed upon and a subsequently printed tag severed from the strip upon each positive or forward stroke of the actuator. The adjacency of the two devices, besides their mechanical advantages, also possess economic value, in that it reduces to a minimum the number of tags between the one, to be printed upon, and the one to be issued from the machine. This avoids printing an excessive number of tags over the supply required.

Another object of my invention is to provide coating cutter members, one having its cutting edge rigid, and the second movable across the first with its cutting edge angular longitudinally to produce a shear-like action transversely through the strip between the cutter members. The cutting edges of the cutters are less in length than the actual length of the tags, and compensation for such discrepancy is had by operating upon a specially prepared tag strip, which results in many advantages for both machine and tag. In the one instance, and to which reference is primarily made herein, the strip comprises a gang of stapled tags, with the tags separated by apertures or notches longitudinally aligned, with the staples of each tag in longitudinal alignment therewith and intermediate of the apertures. The apertures accommodate for the incomplete cutting length of the cutters to obtain a separation of the individual tags from the strip at each cutting stroke of the cutters. This provides a staple clearance at the cutters without auxiliarily moving either of them, and the aperture provides a shoulder to be engaged by a feeding mechanism for advancing the strip.

Various other features, advantages and objects will be readily apparent from the an-

nected drawings forming a part of this specification and from the following detailed description thereof, and comprises a preferred embodiment of the invention, and in such drawings like characters of reference denote corresponding parts throughout the several views, of which:-

Figure 1 is a side elevation of the upper portion of a complete machine. Fig. 2 is an end elevation of Fig. 1, viewed from the left hand side. Fig. 3 is a similar view from the opposite side.

The drawings illustrate only the upper part of the machine, with the base or lower portion, and the stapling mechanism eliminated, but the portion shown is the same as that contained in the aforesaid application, from which this is a division, and to which reference must be had for a disclosure of a complete machine.

The machine finds favor in operating upon a special variety of gang tag strips as articles of commerce. To, however, aid in a clear concept of the present invention, a form having large usage, as disclosed in Letters Patent No. 1130614, issued to me March 2, 1915, is principally referred to herein. Briefly, such gang tag strip comprises, as an article of manufacture, a strip longitudinally divided into tag widths by apertures or notches, preferably in longitudinal proximity with or at one of its marginal edges, which provides a partial severance of each tag. Tag fasteners or staples are secured to the tags in longitudinal alignment intermediate of the apertures or notches, thus coming in line with the pre-severed portions of the tags; they are in position for cutter clearance, and together with the apertures, permit the use of cutters of decreased size, comparative to the length of the tag, and thus enable the rigid mounting of the cutters.

The various devices are supported upon a frame 1, in which an actuator 2 is mounted to reciprocate vertically. The actuator 2, at its upper extremity has a forwardly projecting arm 3, for dependingly supporting a removable type chase or holder 4 above the tag supporting table 5, upon which the tags are guided and fed. The table comprises a bracket or arm projected from the pedestal or frame 1, and may be formed integral therewith. The upper surface of the table provides a suitable guide or channel for the projecting prongs of the staple, and other devices or mechanisms to track and maintain the feed alignment of the tag strip, all of which is more fully disclosed in the said aforementioned application.

Tag-feeding mechanism.—The strip is fed by a spring-pressed finger 6, which engages into notches or apertures of the strip dividing each tag, and the finger is pivotally

mounted upon an arm of the bell crank lever 7, pivoted at 8 to the pedestal 1. The bell crank lever has a notched portion 9 into which a pin 10 projecting from a bar 11 engages, to rock the bell crank lever in the vertical movements of the bar 11. The bar 11 is suitably guided upon the pedestal and secured to the upper portion of the actuator to reciprocate therewith. A spring 12 is secured to the bell crank lever to normalize the same. Thus as the actuator moves in a downward stroke, the bar 11 through its pin 10 will rock the lever to retract the finger and position the same for engagement with a successive notch in the tag strip. Upon the return stroke of the actuator the pin 10 will engage against a projecting abutment 13 upon the bell crank lever to positively rock the bell crank lever and direct the finger in a paper feeding direction, which finger by reason of its downward pressure upon the tag is maintained in engagement with a divisional tag aperture. The feeding mechanism, however, may be of any form to provide an interval of feed at a time operation, and is only concerned herein in its engagement with the strip apertures, and preferably at such apertures providing a partial separation of the individual tags from the strip, or to definitely bring such partially severed portion of the tags in alignment with the cutter mechanism for making a complete severance.

Type-holder.—The type-holder or chase 4 may be of any form of construction which is adapted to be removably connected and rigidly supported dependingly upon the arm 3. As illustrated, the type-holder is provided with laterally projected gibs or ribs projecting from opposite walls of the holder, fittingly engaged with coincident recesses formed in the depending portion 14 of the arm 3. This houses the holder and provides an abutment plate or surface above the type in the holder, against which the type engages in a printing operation, to relieve the holder of any strains from the printing pressure. The holder is of a construction affording convenient removability of each individual type-bar to adapt the same for readily changing the printing data. The holder, as thus mounted, forms a unitary part of the actuator and reciprocates therewith, thereby being positive in its printing operation.

Suitable inking mechanism is provided to ink the type, the form illustrated being that of a ribbon intermittently fed by the movements of the actuator. As the mechanism is auxiliary to the invention herein, detailed description thereof will be omitted, for various forms of inking mechanism may be employed within the province of this invention.

Severing mechanism.—The tag severing mechanism comprises a removable knife blade 15, mounted upon the depending por-

- tion 14 of the arm 3, so as to position the same adjacent the type-holder, to sever subsequently printed tags from the strip immediately adjacent the next successive tag to be printed upon. This offers economy of tags and does not unduly space the tag issued from the one to be printed upon, as heretofore practised in machines of this class, which necessitated waste of several tags after each change of printing data, or very close observation and count has to be resorted to by the operator, to make an early change in the printing data or remove the type-holder. This, however, is not practical in the rapid performances contemplated by the use of machines of this class. Such waste of tags is quite an item in loss to large users and especially when frequent change must be made to the printing data. The cutter blade 15 is provided with two apertures for securing the same upon the actuator, over the pins 16, projecting from the depending portion 14 of the arm 3, and the blade is further secured by a strong leaf spring 18 fastened to the blade and engaged by a catch 19 pivotally projecting from the arm 3.
- The cutting edge of the blade is angular longitudinally and of a length shorter than a comparative length of tag to provide a clearance for the staples fed beneath the rear portion of the blade. The blade moves vertically across the cutting edge of a stationary cutter, which may comprise the edge of the table, or an insert edge secured upon the table to coöperate with the descending cutter blade 15, which latter by reason of its angular edge provides a shear action across the paper.
- The blade 15, likewise as the type-holder, forms a unitary element of the actuator, removable for renewing and sharpening, and is, therefore, positive in its action and operates with the actuator, eliminating auxiliary mechanism to operate the knife as is commonly resorted to in machines of this character. Supporting the type chase and knife rigidly upon the actuator as a unitary component thereof simplifies the construction, increases the life and efficiency thereof, avoids lost motion and produces a superior result, long sought for in this class of ma-
- chines. The reduction of the number of parts is quite a desideratum as it avoids complications commonly arising in machines of 55 a complicated character.
- Having described my invention, I claim:—
1. A machine of the character disclosed, combining a support having a work supporting table, a member mounted to reciprocate upon said support having a rigid laterally extended arm, a type-holder removably, dependingly mounted upon the arm of said member and unitarily moving therewith toward and from said table, a cutter removably mounted upon said member unitarily moving therewith to coöperate with a cutting edge rigid with said table and tension devices retainingly holding said cutter upon its support. 70
2. A machine of the character described, combining a support having a work-supporting table, capable of tracking a gang strip of prestapled tags divisionally apertured for partial separation in longitudinal alinement with the staple, presenting transverse abutments, timed operated feeding devices intervally engaging an aperture to advance the strip, a member mounted to reciprocate upon said support, and a cutter unitarily movable with said member having a cutting edge equal the distance between the inner ends of the apertured portions and the opposite edge of the strip for separating each tag from its strip upon a cutting stroke of said cutter. 85
3. A machine of the character described combining a support having a work supporting table capable of tracking a gang tag strip, the strip divisionally notched from one longitudinal edge to partially separate the tags and providing abutments for feeding mechanism therefor, feeding mechanism for said strip, a movable cutter support and cutter for severing the tags from the strip, said cutter having a cutting edge of a length equal the distance between the apertured portions and the opposite edge of the strip. 95

In witness whereof, I hereunto subscribe my name, as attested by the two subscribing witnesses.

FREDERICK KOHNLE.
